DESIGN FOR A NEGLIGEE

Violet Giovagnoni, New York, N. Y.

Application September 18, 1944, Serial No. 115,333

Term of patent 3½ years

(Cl. D3—26)

To all whom it may concern:

Be it known that I, Violet Giovagnoni, a citizen of the United States, residing in New York city, in the county of New York and State of New York, have invented a new, original, and ornamental Design for a Negligee, of which the following is a specification, reference being had to the accompanying drawing, forming part thereof.

Fig. 1 is a front view of a negligee showing my design,

Fig. 2 is the rear view of the negligee shown in Fig. 1, on a reduced scale, and

Fig. 3 is an enlarged fragmentary view of the negligee shown in Fig. 1 with the reveres in closed position.

I claim:

The ornamental design for a negligee, substantially as shown.

VIOLET GIOVAGNONI.
